ABSTRACT: A beverage dispenser for selectively or concurrently dispensing syrup and carbonated water therefrom. The discharge of such fluids from the dispenser is controlled by a pair of solenoid operated valves respectively associated with switches actuated by levers that depend from the dispenser adjacent the discharge nozzle thereof. The dispenser includes a body structure supporting the various functional components of the dispenser, and a resilient cover slidably related to the body structure is readily removable therefrom to provide access to such switch devices, valve parts, and the solenoid controls for the valves. The dispenser further includes a face piece cooperative with the cover in enclosing such functional components, and the face piece is snap-connected with the body structure so as to be easily removed therefrom in providing access to the functional components of the dispenser.

PATENTED MAY 25 1971

BEVERAGE DISPENSER

DISCLOSURE

This invention relates to a dispenser for portable liquids and, more particularly, to a relatively small, electrically controlled beverage dispenser adapted to discharge either selectively or concurrently a flavoring syrup and carbonated water.

Beverage dispensers of the type in which the present invention resides are relatively small devices and are electrically controlled, having a separate solenoid operated valve and switch therefor controlling the flow of each fluid discharged from the dispenser. Ordinarily, each such dispenser supplies one syrup or flavoring and carbonated water and, therefore, a plurality of dispensers are required in order to provide the selection of beverages necessary to satisfy customer tastes and demand. As a result, the required number of dispensers are arranged in banks each comprising a plurality of dispensers disposed side-by-side proximity and bolted or otherwise fixedly but removably secured to a support plate therefor. In the past, when repair of any one dispenser has been required it has often necessitated removal of the entire dispenser from such support plate, which removal is an inconvenience frequently preventing use of the adjacent dispensers in the bank thereof.

In view of this, a primary object of the present invention is to provide an improved dispenser of the general type discussed affording quick and easy access to the functional components thereof most frequently requiring repair or other maintenance, and which access is afforded without the requirement for removal of the entire dispenser from the support plate therefor and without disturbing adjacent dispensers or interfering in their operation. Additional objects and advantages of the invention, especially as concerns particular features and characteristics thereof, will become apparent as the specification develops.

In effecting the various objects and advantages of the invention, the dispenser provides a body structure equipped with a depending nozzle through which the syrup and carbonated water are discharged. Also depending from the body structure are a pair of levers respectively controlling the discharge of such fluids, and the levers actuate electrical switches in circuit connection with the solenoid controls for the valves which regulate and determine the flow of the fluids from a source of supply therefor to the discharge nozzle. The solenoids, switches, and electrical connections are located within a compartment defined by the body structure and a cover and face piece both cooperative therewith and removable therefrom without the necessity for tools to provide access to such compartment and the components located therewithin. If necessary, such components are readily removable from the body structure for replacement or repair.

An embodiment of the invention is illustrated in the accompanying drawings in which:

FIG. 1 is a broken perspective view of a bank of beverage dispensers embodying the invention, certain components of one such dispenser being shown in exploded, spaced apart relationship;

FIG. 2 is a longitudinal sectional view taken substantially through the center of one of the beverage dispensers;

FIG. 3 is a broken vertical sectional view taken along the line 3-3 of FIG. 2;

FIG. 4 is a broken rear view in elevation taken generally along the line 4-4 of FIG. 2; and

FIG. 5 is a broken longitudinal sectional view taken along the line 5-5 of FIG. 4.

Beverage dispensers embodying the present invention are adapted to be used in groups or banks thereof at a soda fountain or other location at which a variety of beverages are made available for sale to the public because each such dispenser is ordinarily intended to provide for discharge therefrom a single beverage comprising a syrup or flavoring and carbonated water or admixture therewith. It will be evident, then that a dispenser must be provided for each different beverage available for sale. In FIG. 1, three beverage dispensers are illustrated

and they are identical in construction and function. For positive identification, such dispensers are respectively denoted with the numerals 10, 10a and 10b.

Each of the dispensers 10 is secured by cap screws (not shown) to a support plate 11 which is vertically disposed and is equipped at the bottom thereof with a horizontal drainage plate 12 that underlies the dispensers 10 and is adapted to be connected to waste so as to carry thereto any spillage or overflow from the dispensers. The support plate 11 and drainage plate 12 are standard arrangements well known in the art and require no further discussion.

Considering the beverage dispenser 10 in detail, it comprises a body structure 13 which may be formed of any suitable material but in the usual instance will be molded plastic such as clear polycarbonate which is effective to resist corrosion from contact with the citric acids and other ingredients from which the various syrups are made. The body structure 13 is provided with a pair of flow passages 14 and 15 therein enlarged at the rear end of the body structures 13 as respectively shown at 16 and 17 in FIG. 4. The enlarged ends 16 and 17 of the passages define the infeed ends thereto and are adapted to be respectively connected to a source of carbonated water and to a source of syrup as by means of standard harpoon-type connectors which are simply pushed into the enlarged openings through apertures provided for this purpose in the support plate 11.

The passage 14, as shown best in FIGS. 2 and 5, is provided therealong adjacent the enlargement 16 thereof with a metering valve 18 which is threaded into an opening 19 provided therefor in the body structure 13. It will be apparent that the effective cross-sectional area of the passage 14 is determined by adjustment of the metering valve 18 which ordinarily projects slightly into the passage. The metering valve 18 is located intermediate the enlarged infeed end 16 of the water passage 14 and a solenoid operated control valve disposed therealong and generally denoted with the numeral 20.

The valve assembly 20 is conventional and operates to prevent the flow of liquid through the passage 14 until the solenoid is energized whereupon liquid is permitted to flow through such passage at the rate permitted by the metering valve 18. In this respect, the passage 14 enters the valve assembly 20 via a valve or plunger housing 21 along one side thereof and continues through such housing and from the bottom thereof in a generally vertical segment 22 which enters a longitudinal extension 23 terminating at the discharge end thereof in a diffuser 24 having a passage 25 therethrough that opens into the central chamber 26 of a discharge nozzle 27. As shown in FIG. 2, the diffuser 24 is removably secured to the body structure 13 by one or more cap screws 28 and is sealingly related to the body by an O-ring 29. The diffuser 24 threadedly carries the nozzle 27 as shown. Thus, in use of the dispenser, when the solenoid controlled valve 20 is energized, liquid flows from the enlarged end 16 of the passage 14 past the metering valve 18 and valve assembly 20 into the passage segments 22 and 23 and finally through the passage 25 into the nozzle chamber 26 for discharge therefrom into a suitable receptacle therebeneath.

The valve assembly 20 includes a locking plate 30 provided with a plurality of angularly spaced openings therethrough which receive countersunk screws 31 to fixedly secure the plate to the body structure 13, as shown in FIG. 1. The locking plate 30 is equipped with a plurality (three) of upwardly extending ears 32 each of which defines an angularly extending slot 33 adapted to receive therewithin one of a plurality (three) of angularly spaced tongues or lugs 34 provided by a cap 35. The cap 35 is removably secured to the locking plate 30 by angularly displacing the cap relative to the plate to respectively insert the tongues 34 into the slots 33. Release of the cap is effected by displacing it in the opposite direction, and when the tongues are freed from the slots 33, the cap 35 can be lifted from the plate 30.

The plate 30 and cap 35 define a solenoid chamber in which a solenoid 36 is removably mounted. The solenoid as in the

usual case, constitutes multiple turns of a thin wire conductor mounted upon a spool or support having an opening 37 through the center thereof that is adapted to telescopically receive the upper end of the valve housing 21 therein. A valve plunger (not shown) vertically reciprocable within the housing 21 is spring-biased downwardly against a valve seat and into its closed position in which no liquid can flow through the passage 14 and into the passage section 22, and such downward biasing force is imparted thereto primarily by the hydraulic force of the liquid in passage 14 and by a backing plate 38 and spring (not shown). It may be observed that the housing 21 has a laterally extending flange underlying the locking plate 30 and is held thereby in proper position with respect to the body structure 13. An O-ring 39 sealingly relates the housing to the body structure within the opening provided therefor.

The solenoid controlled valve 20 is energized through a switch device 40 which may be a conventional microswitch or other small on-off switch electrically connected with the solenoid 36 by conductors 41. The switch 40 is actuated by an elongated lever 42 that extends downwardly from the body structure 13, as shown in FIGS. 1 and 2, and is adapted to be displaced rearwardly by a glass or other receptacle placed beneath the nozzle 27 to receive the liquid discharged therefrom. It might be observed at this point that an identical solenoid switch device and lever therefor are associated with the syrup passage 15, and in view of the structural and functional correspondence of these devices those associated with the syrup passage 15 are respectively denoted with the primed form of the same numerals used to identify the components associated with the water passage 14.

Accordingly, and referring to FIG. 1, it will be noted that the lever 42' is pivotally supported intermediate the ends thereof on a pin 43' provided by the body structure 13, and such lever 42' is resiliently biased in a substantial vertical orientation by a leaf spring 44' forming a part of the switch 40'. Therefore, when a beverage glass is placed beneath the nozzle 27 it can be used to displace one or the other or both of the levers 42 and 42' rearwardly against the biasing force of the respectively associated leaf springs to actuate the switch devices 40 and 40' thereof and energize the respectively associated solenoid controlled valves 20 and 20'.

As shown most clearly in FIG. 3, the switch devices are readily positioned upon or removed from the body structure 13 by means of a pair of spaced apart pins 45' and 45' (considering the switch 40') respectively receivable within openings or bores 47' and 48' formed in the switch 40'. The body structure 13 is provided along each side thereof with a recess or inset area, 49 and 49', which seats the respectively associated switch device and levers 40, 42 and 40', 42' therein. Accordingly, the switch devices are conveniently removable for repair or replacement whenever this is necessary. Respecting removability, as shown in FIGS. 1 and 2, the caps 35 and 35' of the solenoid valves 20 and 20' are locked in place and grounded by a strap 50 which is mechanically and electrically connected to the cap by screws 51 and 51' and is released by loosening these screws.

Respecting the passage 15, it is provided with a metering valve 18' therealong, and such passage enters the housing 21' of the valve assembly 20' through a lateral opening 52 therein, as shown in FIG. 2. Liquid entering the housing 21' flows downwardly therethrough, when permitted by the position of the associated valve plunger (not shown), into the central opening 53 in the aforementioned diffuser 24 and into a diffuser component 55 held in position by the aforementioned cap screws 28. The openings 53 and 54 are serially related and communicate with the central opening 26 in the diffuser 27, through angularly spaced openings 54 through the sidewall of diffuser component 55. The solenoid controlled valve 20' is energized through the switch 40' and lever 42' associated therewith, and the lever can be manipulated by a glass or other receptacle positioned beneath the nozzle 27.

The dispenser 10 is provided at the forward end thereof with a light 56 removably carried by a mounting block 57 screwed or otherwise secured to the body structure 13. The light 56 illuminates the front of the dispenser and any indicia provided along the face 58 of a face piece 59 forming the forward wall of the dispenser 10, as shown in FIG. 1. The face piece 59 is removably secured to the body structure 13 by a tongue and groove type fastener provided along each side of the face piece. Such fasteners are illustrated in FIG. 1, and each is seen to comprise a pair of spaced apart prongs 60 and 61 that may be formed integrally with the face piece and define a somewhat arcuate receptacle or opening 62 therebetween which is adapted to releasably seat therein a pin or tongue 63 extending outward from the body structure 13 within the recess 49' (or 49) provided therealong. The prongs 60 and 61 are sufficiently resilient so as to spread and permit the pin 63 to pass therebetween and into the receptacle 62 whereupon the prong snugly grips the pin. However, when the face piece is grasped and sufficient force applied thereto in a direction away from the body structure 13 the prongs again spread and permit the pin 63 to pass therebetween to release the face piece from the body structure.

The dispenser 10 further comprises a cover or shroud 64 which has an inverted generally U-shaped configuration and is somewhat resilient so as to impart an inwardly directed force to the depending sidewalls 65 and 66 thereof. In this respect, the cover 64 may be formed of stainless steel, and for esthetic purposes and to strengthen the same, the sidewalls 65 and 66 are respectively provided therealong with longitudinally extending inwardly deformed ribs 67 and 68. At their lower edges, the walls 65 and 66 are respectively equipped with inwardly turned lips 69 and 70 adapted to slidably underlie the respectively associated planar edge portions 71 and 72 provided by the body structure 13 along the bottom thereof.

In use of the beverage dispensers 10, one or more thereof are secured to a support plate 11 by cap screws extending therethrough and into openings 73 (FIG. 4) provided along the rear wall of the body structure 13. Carbonated water and syrup are connected to the passages 14 and 15, and suitable electrical connections are made to each dispenser to a power cord 74 that also extends through an opening provided for this purpose in the plate 11. Such a power cord is usually a 3-wire cable including a ground wire and the opposite sides of the power circuit for the solenoids and light. The particular beverage supplied by any dispenser is discharged from the nozzle 27 upon placing a glass beneath and displacing one or the other or both of the levers 42 and 42' to permit the flow of syrup and carbonated water into the nozzle chamber 26, all as is standard and well known.

Should it be required to repair or otherwise service the dispenser, access to the working components thereof is quickly gained by removing the face piece 59 from the body structure 13 which face piece snaps freely from the pins 63 provided by the body structure upon application of a force of sufficient magnitude to the face piece. Upon removal of the face piece 59, the cover 64 is simply slid forwardly to withdraw it from the body structure 13, whereupon the compartment otherwise defined by the body structure, cover and face piece is open and access to the solenoid controlled valves 20 and 20' and to the switches 40 and 40' is afforded. The switches 40 and 40' can be removed from the body structure 13 simply by gripping the same and pulling them in a transverse direction to remove the pins 45 and 46 from the openings 47 and 48 in the switch device. The solenoids are made available by loosening the screws 51 and 51' to remove the ground strap 50 whereupon the caps 35 and 35' can be removed by rotation of the same a short angular distance to separate the tongues 34 from the slots 33.

When the caps 35 and 35' have been removed, the solenoids 36 and 36' can be lifted upwardly from the housing 21 and 21'; and should the valve plungers need to be removed for cleaning, they are simply withdrawn upwardly through the housings 21 and 21'. The electric light 56 can be replaced

without removing the cover 64 since access is provided thereto upon removal of the face piece 59. The dispenser is reassembled after the solenoid controlled valves and switch devices are in place simply by sliding the cover 64 into position along the body structure 13 and then snapping the face plate 59 into place. As shown in FIG. 1, when the cover 64 is in place it telescopically receives the rear wall of the body structure 13 therewithin and it similarly telescopically receives the side and top wall segments 75 of the face piece 59 therewithin.

Thus, when assembled, a streamlined, integrated and integrally appearing unit is provided and access to the working components thereof is readily obtained by removing the face piece 59 and cover 64. Clearly, access to the working components of any one of the beverage dispensers in a bank thereof is attained in the manner described without disturbing or interfering with continued use of the adjacent dispensers.

While in the foregoing specification an embodiment of the invention has been described in considerable detail for purposes of making a complete disclosure thereof, it will be apparent to those skilled in the art that numerous changes may be made in such details without departing from the spirit and principles of the invention.

I claim:

1. A beverage dispenser having a downwardly opening nozzle through which fluids are selectively discharged into a receptacle held therebelow, comprising a body structure to which said nozzle is attached, a cover removably secured to said body structure and defining a compartment therewith along the upper side thereof, said cover comprising an inverted generally U-shaped component slidably and resiliently gripping said body structure, a face piece removably secured to said body structure along the forward end thereof and cooperative with said cover in the formation of said compartment, said body structure being provided with a plurality of flow conduits leading to said nozzle and adapted to be respectively connected to supplies of such fluids, and solenoid controlled valve assemblies and switch devices therefor respectively associated with said flow conduits to control the flow of fluids therethrough and being located within said compartment, whereby removal of said face piece and cover provides access to said valve assemblies and switch devices without removing said body structure from a support therefor.

2. The beverage dispenser of claim 1 in which said body structure has generally planar edge portions along the bottom thereof, and in which said cover has inwardly turned lips slidably engageable with said edge portions.

3. The beverage dispenser of claim 1 and comprising an upwardly extending support plate and a plurality of the aforesaid beverage dispensers each provided with a body structure secured along the rear end thereof to said support plate, said dispensers being disposed in relatively close juxtaposition and aligned to form a bank thereof, the cover and face piece of any one of said dispensers being removable therefrom without interfering with the others.

4. The beverage dispenser of claim 3 in which each of said body structures has generally planar edge portions along the bottom thereof, and in which each of said covers has inwardly turned lips slidably engageable with the associated edge portions, each of said face pieces being provided with a plurality of snap fasteners and each body structure being provided with posts respectively associated with said fasteners to releasably secure said face pieces to said body structures.

5. The beverage dispenser of claim 4 in which said solenoid controlled valve assemblies and switch devices are removably attached to the respectively associated body structures to facilitate repair of each of said beverage dispensers.

5. The beverage dispenser of claim 5 in which each of said switch devices is provided with an aperture therethrough, and in which each of said body structures is equipped with a plurality of pins respectively associated with said switch devices and being receivable within the openings therethrough to positively locate and mount the switch devices along the associated body structures.

7. A beverage dispenser having a downwardly opening nozzle through which fluids are selectively discharged into a receptacle held therebelow, comprising a body structure to

15 upper side thereof, a face piece removably secured to said body structure along the forward end thereof and cooperative with said cover in the formation of said compartment, said body structure being provided with a plurality of flow conduits leading to said nozzle and adapted to be respectively connected to supplies of such fluids, solenoid controlled valve assemblies and switch devices therefor respectively associated with said flow conduits to control the flow of fluids therethrough and being located within said compartment, whereby removal of said face piece and cover provides access

20 to said valve assemblies and switch devices without removing said body structure from a support therefor, each of said switch devices being provided with an aperture therethrough, and said body structure being equipped with a plurality of pins respectively associated with said switch devices and being receivable within the opening therethrough to positively locate and mount the switch devices along said body structure.

30 8. The beverage dispenser of claim 7 in which said solenoid controlled valve assemblies and switch devices are removably attached to said body structure to facilitate repair of said beverage dispenser.

35 9. The beverage dispenser of claim 8 in which each of said switch devices is provided with an aperture therethrough and in which said body structure is equipped with a plurality of pins respectively associated with said switch devices and being receivable within the opening therethrough to positively locate and mount the switch devices along said body structure.

10. A beverage dispenser having a downwardly opening nozzle through which fluids are selectively discharged into a receptacle held therebelow, comprising a body structure to

45 which said nozzle is attached, a cover removably secured to said body structure and defining a compartment therewith along the upper side thereof, a face piece removably secured to said body structure along the forward end thereof and cooperative with said cover in the formation of said compartment, said face plate being provided with a plurality of snap

50 fasteners and said body structure being provided with posts respectively associated with said fasteners to releasably secure said face piece to said body structure, said body structure being provided with a plurality of flow conduits leading to said

55 nozzle and adapted to be respectively connected to supplies of such fluids, and solenoid controlled valve assemblies and switch devices therefor respectively associated with said flow conduits to control the flow of fluids therethrough and being located within said compartment, whereby removal of said face piece and cover provides access to said valve assemblies and switch devices without removing said body structure from a support therefor.
